UNITED STATES PATENT OFFICE.

HENRY MYERS, OF PHILADELPHIA, PENNSYLVANIA.

TRUNK-EDGE PROTECTOR.

1,134,219.

Specification of Letters Patent.

Patented Apr. 6, 1915.

Application filed September 27, 1912. Serial No. 722,587.

To all whom it may concern:

Be it known that I, HENRY MYERS, a citizen of the United States, residing at 314 North Tenth street, Philadelphia, in the 5 county of Philadelphia and State of Pennsylvania, have invented a certain new and useful Trunk-Edge Protector, of which the following is a specification.

The purposes of my invention are to additionally stiffen the edge and corner constructions of trunks.

A further purpose of my invention is to fasten a stiff metal edge to the material of a trunk much more securely than has been 15 possible hitherto obtaining a minimum of weight with great rigidness.

A further purpose of my invention is to unite two approaching metal edge strips by a diagonal brace near a corner and, preferably, to stiffen this brace and a corner guard or buffer mutually by connecting them together.

Further purposes of my invention will appear from the specification and particularly from the claims thereof.

I have preferred to illustrate my invention by one form thereof which has proved to be practical, efficient and inexpensive and which at the same time well illustrates the 30 principles involved.

Figure 1 is an end elevation of a trunk showing the preferred form of my invention. Fig. 2 is a perspective, partly in section of a trunk corner embodying my invention, the 35 corner buffer being omitted. Fig. 3 is a broken end elevation, partly in section of a corner such as is shown in Fig. 1, the buffer being dotted in position. Fig. 4 is a broken section of two meeting trunk sides showing 40 the edge stiffening used.

Metal edging, to be effective, requires a strip having enough thickness to secure the requisite rigidity; and must, therefore, be quite narrow to avoid excessive weight.

45 Since a trunk is essentially a box and the covering is built upon and about the box, this lining material has interfered with riveting the edge strips or stiffeners to the body of the trunk. Moreover, the difficulty of 50 getting at the parts for machine riveting has also discouraged such construction even if it were otherwise practicable. As a result, the stiff metal edging in current use is not only tacked on, but is tacked along one 55 only of the two flanges at right angles which comprise the edging. Tacks in the other

flange would lie too close to the joint between the wooden frame parts for appreciable advantage from them. As the wood dries out, the tacks lose part of their hold. 60 As an additional precaution it is customary to inclose the strips at intervals by edge brackets which are tacked in place. These are exterior, discontinuous, heavy and expensive. 65

I purpose attaching the heavy metal edging rigidly to a light but strong and considerably wider additional edge stiffener, also of angular form, under circumstances such that this attachment may be made rigid and 70 more permanent, permitting it to be done conveniently by machine riveter, for example. By this construction the additional stiffener may be attached to the body of the trunk at a much greater distance from the 75 edge than could be the case with the metal edging without excessive weight for the metal, obtaining the additional leverage corresponding to the additional distance from the edge in resisting strains of what- 80 ever character.

I have shown my invention as applied to an edge and corner of a trunk for convenience of illustration, but obviously it could be used with substantially equal advantage 85 in other box-like structures and with other meeting angles than right angles.

I illustrate a trunk whose body is formed so far as shown of the top board 1, side board 2, and end 3, covered ordinarily with 90 fiber or other suitable light protective material shown at 4, 5 and 6. I have shown the edges as meeting at a right angle and have correspondingly applied right angular edge protection. This is shown in the form of a 95 fiber angle 7, having flanges 8 and 9, and a metal angle 10, having flanges 11 and 12.

The flanges 11 and 12 are preferably riveted to the flanges 8 and 9, as at 13, and are secured to the latter before these fiber 100 flanges are secured to the body of the trunk. Wherever the exigencies of use require I purpose using permanent rivet fastenings for the fiber also, as at 13', but find that it is sufficient ordinarily to tack them to the body 105 of the trunk, since they can be tacked at any desired intervals without the necessity for previous perforation of the material, and the distance from the tacks at 14 to the edge line 15 at which the strains are presented is permissibly great enough to keep the strain upon each tack quite low. The 110

fact that both flanges of my metal edging 10 are attached to the trunk, (through the intermediate preferably fiber angle) at reasonable intervals makes it possible for me to avoid the use of retaining clamps or frames such as are so generally employed with the present construction.

At the corners, where two angles meet, I prefer to place an angle strap which I have shown as comprising arms 16 and 17, uniting its arms to the several angles preferably by any suitable means, which may be the same means by which the latter are united to the auxiliary wider preferably fiber edging.

Whether any corner angle be used or not, I prefer to unite the angles in one or more of the three planes formed in each corner by a stiffening brace, extending between those flanges of the meeting angles which lie in the same or substantially parallel planes, here illustrated by the braces 18, extending between flanges as 11, and preferably united to the flanges by the same means which unites these flanges to the flanges 8, 8 25 of the preferably fiber auxiliary edge protector.

I prefer to use trunk corners of some one of the recognized present forms at the corners, whether or not I make use of the corner-connecting flanges 16, 17, and have illustrated a conventional corner at 19. Whatever the form of corner used and whatever the number of openings 20 provided in the plate 21 by which it is intended to be secured to the body of the trunk, I prefer to secure this inner member 21 to the brace 18 and can do this with the least trouble by using the same fastenings for the purpose as those used to secure the plate 21 to the trunk, these fastenings being conventionally shown at 22. While it may be desirable to brace in all of the three planes at each corner equally this will not be necessary in all constructions. Both the braces 45 and connecting plates such as 21 may be omitted in some of the planes, as in Fig. 1, or the braces used in one or more of the planes; as at 18', Fig. 2, without connection with the trunk corner buffer as purposed 50 at 18', which lacks the intermediate perforations; or other combinations of the stiffening means shown by me may be supplied within the discretion of the maker in view of the needs, intended use and other 55 structure of the trunk which is being designed.

The brace or braces 18 or 18' rigidly support the corner angles in relation to each other, and may at the same time retain the corner buffer firmly in position. The corner piece or buffer, wherever connected to the strap by a plate, co-operates to stiffen the brace against diagonal strains away from the corner and overlaps the brace, protecting 65 it in this way also.

It will be evident that the co-action of the protective edge angles with the braces, as 18 or 18' and both with the corner buffer, as 20 is present whether or not the auxiliary edge-protecting angles be present but is 70 highly beneficial in connection with the auxiliary edge-protecting flanges, inasmuch as these make it possible to attach the individual metal flanges with greater security not only at the corner itself but in supporting 75 proximity to it along the edge.

It will be evident that the three edge strips or angles are held together both by the corner piece and by the diagonal strips 18, 18' and that the corner piece additionally 80 protects the frame near the corner because of its attachment to the diagonal strips by means of the plates or extensions 21.

Having thus described my invention, what I claim as new and desire to secure by Letters Patent is:

1. In a device of the character stated, a trunk body, a pair of edge strips therefor meeting in a corner, a diagonal strip joining the corner strips near their meeting point, a corner piece fitting over the meeting portions of the edge strips, an extension of said corner piece secured to the diagonal strip and means for securing the strips and corner piece to the trunk. 95

2. In a device of the character stated, a trunk body, three edge strips meeting in a corner, diagonal strips joining the edge strips in the three planes represented, a corner piece covering the meeting ends of the 100 edge strips, three extensions from the corner piece joined to the diagonal strips and means for securing the strips and corner piece to the trunk.

3. In a device of the character stated, a 105 trunk body having a corner, main and auxiliary edge-protecting angles along two of the edges united to form the corner, having one flange of each along one edge in a substantially parallel plane with one flange of 110 each along the other edge and a brace joining these flanges at a distance from the corner and united to them.

4. In a device of the character stated, a trunk body having a corner, edge-protecting 115 angles along two of the edges uniting to form the corner having one flange along one edge in a substantially parallel plane with one flange along the other edge, a brace joining these flanges at a distance from the 120 corner and united to them and a corner buffer having an extension diagonal to the meeting flanges and united to the brace.

5. In a device of the character stated, a trunk body, covering material therefor, a 125 pair of rigid edge protecting angles for two edges joining in a corner, means for uniting the edge protecting angle with the body, a second pair of edge protecting angles having narrower flanges than the first angles, 130

means for uniting the two sets of angles separate from the trunk body, a strip engaging flanges of different angles of the second pair of strips lying in substantially parallel planes, said strip extending transversely across the corner, means uniting the strip to the flanges of said angles, a corner

buffer extended to engage with the strip and uniting means for the buffer and strip.

HENRY MYERS.
